A. J. MILLS AND E. M. HEWETT, OF SCOTT, NEW YORK.

Letters Patent No. 64,129, dated April 23, 1867.

IMPROVED CLOTHES-DRYER.

The Schedule referred to in these Letters Patent and making part of the same.

TO ALL WHOM IT MAY CONCERN:

Be it known that we, A. J. MILLS and E. M. HEWETT, of Scott, in the county of Courtland, and in the State of New York, have invented certain new and useful improvements in "Clothes-Dryers;" and do hereby declare that the following is a full, clear, and exact description thereof, reference being had to the accompanying drawings and to the letters of reference marked thereon.

In the drawings, A' represents a thin metallic plate, with a series of semicircular flanges, A A, cast upon it. C C represent ears, which are also cast upon the plate, one at each end and one upon each side. These ears are provided with holes through which screws pass, or nails to secure the plate to the wall of a house, or to any place it may be desirable to secure it. B B represent a series of wooden bars, the inner ends of which are pivoted between the flanges A A by means of the pins d d. There are two sets of these bars, as will be seen, passing in between the flanges from each side of the plate, and their ends nearly meeting before they are secured by the pins. The flanges are cast sufficiently wide apart to allow a slat of any required thickness to be placed between them, and are cast sufficiently deep to act as a support for the slat when it is opened out to receive clothes upon it.

In using this dryer the plate A' is nailed or screwed to the wall of the room in which it is intended to be used, its back being flat against the wall. The slats are then opened out at any desired angle and clothes are hung upon them to be dried. When the slats are not in use they may be closed up to the wall so as to be entirely out of the way.

Having thus fully described our invention, what we claim as new, and desire to secure by Letters Patent, is—

The within-described dryer, composed of the plate A', with its flanges, and the pivoted slats B B, the same being used substantially as and for the purpose specified.

In testimony that we claim the foregoing we have hereunto set our hands.

A. J. MILLS,
E. M. HEWETT.
